The ornamental design for towing attachment for vehicles, as shown and described.

DESCRIPTION

FIG. 1 is a top perspective view of the towing attachment for vehicles of the present invention showing our new design; FIG. 2 is a bottom perspective view thereof;

FIG. 3 is a side view thereof, the opposite side views being identical;

FIG. 4 is a front view thereof;

FIG. 5 is top plan view thereof; and,

FIG. 6 is a bottom view.

The broken lines illustrate portions of the towing attachment for vehicles that form no part of the claimed design.
